UNITED STATES PATENT OFFICE

152,053

DESIGN FOR A BOTTLE CARRIER

Albert L. Barnes, Longview, Wash.

Application April 18, 1947, Serial No. 138,474

Term of patent 3½ years

(Cl. D58—4)

To all whom it may concern:

Be it known that I, Albert L. Barnes, a citizen of the United States, residing at Longview, in the county of Cowlitz and State of Washington, have invented a new, original, and ornamental Design for a Bottle Carrier, of which the following is a specification, reference being had to the accompanying drawings, forming part thereof.

Figure 1 is a side elevational view of a bottle carrier, showing my new design, and

Figure 2 is a top plan view thereof.

I claim:

The ornamental design for a bottle carrier, as shown.

ALBERT L. BARNES.
